(57) **CLAIM**

The ornamental design for a dish rack, as shown and described.

DESCRIPTION

FIG. 1 is a perspective view of the present invention dish rack;

FIG. 2 is a right side elevational view of the dish rack;

FIG. 3 is a left side elevational view of the dish rack;

FIG. 4 is a top plan view of the dish rack

FIG. 5 is a bottom plan view of the dish rack

FIG. 6 is a front elevational view of the dish rack; and,

FIG. 7 is a rear elevational view of the dish rack.

It should be appreciated that the broken line illustrations of dishes and eating utensils shown in FIG. 1 and portions of the dish rack shown in FIG. 4 are for illustrative purposes only and form no part of the claimed invention.
